(57) **CLAIM**

I claim the ornamental design for a faucet spout, as shown and described.

DESCRIPTION

FIG. 1 is a Perspective view of a faucet spout showing my new design;

FIG. 2 is a Front view of the faucet spout as shown in FIG. 1;

FIG. 3 is a Back view of the faucet spout as shown in FIG. 1;

FIG. 4 is a Right-side view of the faucet spout as shown in FIG. 1;

FIG. 5 is a Left-side view of the faucet spout as shown in FIG. 1;

FIG. 6 is a Top view of the faucet spout as shown in FIG. 1; and,

FIG. 7 is Bottom view of the faucet spout as shown in FIG. 1.

The broken lines shown in the drawing views are included for the purpose of illustrating portions of the faucet spout and forms no part of the claimed design.
